Primary Examiner — Leanne Was-Englehart*Assistant Examiner* — Justin A Johnson(74) *Attorney, Agent, or Firm* — Knobbe, Martens, Olson & Bear, LLP(57) **CLAIM**

The ornamental design for a paintball mask, as shown and described.

DESCRIPTION

FIG. 1 is a front perspective view of a paintball mask, according to my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

Broken lines are used to illustrate features of the paintball mask which form no part of the claimed design.

1 Claim, 7 Drawing Sheets(56)
